[57] CLAIM

The ornamental design for a telephone dialing apparatus, as shown and described.

DESCRIPTION

FIG. 1 is a front and right side perspective view of a telephone dialing apparatus showing our new design;

FIG. 2 is a right side elevational view;

FIG. 3 is a left side elevational view thereof;

FIG. 4 is a front elevational view of the telephone dialing apparatus;

FIG. 5 is a rear elevational view thereof;

FIG. 6 is a top plan view; and

FIG. 7 is a bottom plan view thereof.

The broken line showing of a person's head in FIGS. 1, 4 and 6 is for illustrative purposes only and forms no part of the claimed design.

FIG. 1

FIG. 2

FIG. 3

FIG. 4

FIG. 5

FIG. 6

FIG. 7
